INVENTOR.

UNITED STATES PATENT OFFICE.

JOHN C. HALL, OF CINCINNATI, OHIO.

DESIGN FOR A CRIB-CHAIR.

Specification forming part of Design No. 6,283, dated December 10, 1872.

To all whom it may concern:

Be it known that I, JOHN C. HALL, of Cincinnati, Hamilton county, Ohio, have invented and produced a new and original Design for a Folding Crib-Chair, of which the following is a specification:

The nature of my design is fully represented in the accompanying photographic illustration, to which reference is made, and in which the accompanying illustration represents chair in its opened condition.

Claim.

I claim as my invention—
The design for a folding crib-chair, as shown.
In testimony of which invention I hereinunto set my hand.

JNO. C. HALL.

Attest:

GEO. H. KNIGHT,
JAMES H. LAYMAN.
